PICKER STICK CHECK FOR LOOMS

Lewis W. Hodge, Phenix City, Ala., and Robert B. Hodge, Atlanta, Ga.

Application June 30, 1933, Serial No. 678,514

2 Claims. (Cl. 139—169)

This invention relates to looms and its general object is to provide a picker stick check that can be adjustably secured to the lay of the loom for disposal in the path of the picker stick to yieldably check the motion thereof, in a manner which will result in increased production and a better quality of cloth.

A further object of the invention is to provide a picker stick check, that is simple in construction, inexpensive to manufacture, easy to apply to various types of looms and is extremely efficient in operation and service.

This invention also consists in certain other features of construction and in the combination and arrangement of the several parts, to be hereinafter fully described, illustrated in the accompanying drawing and specifically pointed out in the appended claims.

In describing our invention in detail, reference will be had to the accompanying drawing wherein like characters denote like or corresponding parts throughout the several views, and in which:

Figure 1 is a side view illustrating my check applied to the lay of a loom.

Figure 2 is a front view thereof.

Figure 3 is a perspective view of the stop member.

Referring to the drawing in detail, the letter A indicates the lay of a loom and to which we have shown our device secured for arrangement in the path of the picker stick B, as clearly shown in Figure 1 of the drawing.

Our device includes a bracket provided with a relatively long body strip 1 having arranged thereon in a pair of spaced slots and an opening for the purpose of receiving the bolts of bolt and nut connections 2, for adjustably securing the strip to the underside of the lay. Formed on or otherwise secured to the body strip 1 and depending therefrom as well as terminating at its free end in substantial parallelism therewith is an arm 3 having an opening in its free end.

Extending through the opening is a relatively long bolt 4 that is secured to the arm 3 through the instrumentalities of nuts arranged upon opposite sides of the arm and while we have shown one lock washer, it will be apparent that more may be applied if necessary. The head 5 of the bolt is formed thereon in a manner to be disposed off-center as clearly shown in Figure 2.

Pivotedly mounted on the bolt 4 is a finger or buffer member 6 which includes a bearing portion 7, and arranged in the bearing portion 7 is a bushing which takes the wear, with the result the bushing can be replaced from time to time and the

buffer member will last for a prolonged period of time without replacement. The finger is relatively long and is curved to a considerable degree. Secured to the outer curved face is a strip 8 of leather or like material, and the finger is provided with a reinforcing rib 9 on its inner curved face as clearly shown in Figure 1.

The strip covered face is arranged in the path of the picker stick B to yieldably receive the latter and the yieldable action is brought about through the instrumentality of a coil spring 10 which surrounds the bolt 4 and has one end fixed to the head 5, while its opposite end portion is disposed about the buffer member 6 as best shown in Figure 2, so as to normally hold the buffer member in a forward position to receive the picker stick and to gradually retard its motion.

Disposed between the inner nut of the bolt 4 and the free end of the arm 3 is one portion of a stop member 11 which is likewise fixed to the bolt through the instrumentality of the nuts, and disposed at right angles to the first mentioned portion of the stop member is a transversely curved portion 12 that follows the curvature of the bearing portion of the buffer member. The curved portion of the stop member is arranged within the path of the finger portion of the buffer member to limit its inward movement, with the result the strip covered face will be at all times disposed to receive the picker stick in the manner as clearly shown in Figure 1.

From the above description and disclosure of the drawing, it will be obvious that we have provided a picker stick check for looms that will gradually retard the motion of the picker stick, and thereby causes an easy and gentle stoppage thereof which is absolutely necessary to produce cloth of high quality, and of course that action tends to increase production to a considerable extent.

It is thought from the foregoing description that the advantages and novel features of our invention will be readily apparent.

We desire it to be understood that we may make changes in the construction and in the combination and arrangement of the several parts, provided that such changes fall within the scope of the appended claims.

What we claim is:

1. A picker stick check for a loom comprising a buffer member including a curved finger portion having a face covered with resilient absorbent material, bracket means for supporting the buffer member with the covered face in the path of the picker stick of the loom, a relatively long body

strip included in the bracket means, means for adjustably securing the body strip to the loom, an arm extending from the body strip and terminating in substantially parallelism therewith, a bolt extending through the free end of the arm and pivotally receiving the buffer member, tensioning means for said buffer member and secured to the bolt and stop means to limit the movement of the buffer member in one direction and secured to the bolt.

2. A picker stick check for a loom comprising a buffer member including a curved finger portion having a covered face, a bearing portion included in the buffer member, a bolt for receiving the

15

bearing member for pivotal movement thereon, stop means for said buffer member to limit its movement in one direction and secured to the bolt, a coil spring surrounding the bolt and having one end fixed thereto and its opposite end portion secured to the buffer member to put the latter under tension and to limit its movement in an opposite direction, and a bracket having connection with the bolt for supporting the latter with the covered face of the buffer member in the path of the picker stick of the loom.
